(57) **CLAIM**

The ornamental design for a lavatory, as shown and described.

DESCRIPTION

FIG. 1 is a front perspective view of a lavatory showing my new design;

FIG. 2 is a front view of the lavatory shown in FIG. 1;

FIG. 3 is a right side view of the lavatory shown in FIG. 1 (with the left side view being a mirror image thereof)

FIG. 4 is a top view of the lavatory shown in FIG. 1; and,

FIG. 5 is a bottom view of the lavatory shown in FIG. 1. The broken lines showing lavatory legs, handles and circular sink cut-out illustrate portions of the lavatory that form no part of the claimed design.

The rear of the design is plain and unornamented.
